UNITED STATES PATENT OFFICE.

GEORGE E. GLOSSOP, OF OTTAWA, ONTARIO, CANADA, ASSIGNOR OF ONE-HALF TO
JOSEPH R. B. McCREARY, OF OTTAWA, ONTARIO, CANADA.

HEADLIGHT.

Application filed October 18, 1922. Serial No. 595,344.

To all whom it may concern:

Be it known that I, GEORGE E. GLOSSOP, a citizen of Dominion of Canada, and resident of Ottawa, in the county of Carleton and Province of Ontario, Dominion of Canada, have invented certain new and useful Improvements in Headlights, of which the following is a specification.

This invention has relation to certain new and useful improvements in headlights and has for its primary object the provision of a type of headlight which will throw to one side and at the same time to the front a diffused light, which will be practically as bright at the side as at the front, the light being also directed downwardly onto the surface.

Another object of the invention resides in the provision of a headlight of the character stated, which will be constructed in such a manner that direct rays, known as spotlights will be avoided.

Another object of the invention resides in the provision of a headlight of the character stated in which the lens will be of concavo-convex form and practically a continuation of the curved reflector and provided with central and side prisms for deflecting the light rays passing through the lens.

A further object of the invention resides in the provision of a headlight of the character stated, which will be constructed in such a manner as to refract and deflect downwardly and sidewise the maximum number of light rays passing directly from the lamp bulb through the lens.

A further object resides in the provision of a headlight of the character stated, which will be of simple construction and operation, composed of the minimum number of parts and highly efficient in use, operating at all times to throw downwardly a diffused light to the side, as well as straight, ahead of the lamp.

A still further object of the invention resides in the provision of a headlight of the character stated, which is constructed in such a manner that the entire rear part of the lamp structure serves as a reflector while the lens constitutes the greater portion of the front part of the lamp structure and may be readily attached to the reflector and the drum casing, enclosing the reflector, the

lamp bulb being suspended from one of the parts of the lamp structure and located concentrically of the reflector.

A still further object of the invention resides in the provision of a headlight of the character stated, which is constructed in such a manner that any of the parts thereof may be readily replaced or repaired without injury to the other parts.

With the foregoing and other objects in view, as will appear as the description proceeds, the invention consists in the novel construction, combination and arrangement of co-operating elements, as hereinafter more specifically set forth, claimed and shown in the accompanying drawings forming a part of the present application, in which:

Fig. 1 is a plan of the forward portion of a motor vehicle with a pair of headlights of the improved type mounted thereon.

Fig. 2 is a front elevation of one of the headlights.

Fig. 3 is a side elevation of the headlight.

Fig. 4 is a vertical section through the headlight, substantially on the plane of line 4—4 of Fig. 2, looking in the direction indicated by the arrows.

Fig. 5 is a transverse horizontal section substantially on the plane of line 5—5 of Fig. 3, looking in the direction indicated by the arrows.

Fig. 6 is a view similar to Fig. 5, showing a modified form of the invention.

Fig. 7 is a view similar to Figs. 5 and 6, showing a further modification.

Fig. 8 is a vertical section through the form disclosed in Fig. 7.

Referring more in detail to the drawings in which similar reference characters designate corresponding parts throughout the several views, 10 designates the reflector which is of substantially semi-spherical form and which is positioned in the cylindrical drum casing 11 and detachably secured thereto by the attaching means 11', or by any other suitable means or method, as desired. The cylindrical drum casing 11 has an open forward side, with the edge of which, one side of the forward edge of the reflector 10 registers, as shown in Fig. 5. The reflector 10 is turned in such a manner within the drum casing 11, that the other side of the forward edge of the reflector 10

is positioned inwardly of the corresponding portion of the forward edge of the cylindrical drum casing 11. This may be readily seen by referring to Fig. 5. By turning the reflector 10 to one side as stated, the front part 12 of the lamp structure will also be turned to the side as the edge of this front part 12 is engaged against the forward edge of the reflector 10. An annular flange 13 is carried on the front part 12 for engagement against the flanged forward edge 14 of the cylindrical drum casing 11, after which the transversely split clamping ring 15 is placed over the annular flange 13 and the flanged forward edge 14 and securely tightened thereon, by means of the clamp screw 16 extended through the parallel offset ends 17 of the transversely split clamping ring 15, as shown clearly in Fig. 2. This will serve to securely hold the front part 12 in proper position at the front of the cylindrical drum casing 11 and in engagement with the reflector 10. The annular flange 13 is extended at an angle with respect to the rear edge of the front part 12, to permit one side of the latter to extend into the cylindrical drum casing 11 and engage the reflector 10. This entire structure may be readily seen by referring to the drawings, particularly Fig. 5. It will also be seen from the drawings, that a cushioning ring 18 is extended around the reflector 10 and the front part 12 within the cylindrical drum casing 11 and at the forward open side thereof, to properly retain the parts in normal position and prevent unnecessary vibration or movement thereof.

The lens 19 employed in the construction of this lamp is of concavo-convex form in horizontal section, as well as in vertical section. This can also be seen from Figs. 4 and 5. The lens 19 is positioned with its convex side turned out and arranged concentrically to the lamp bulb 20, which latter is also suspended concentrically of the reflector 10, thereby bringing the lamp bulb 20 opposite the edge or near the edge of the reflector 10, as shown in Fig. 5. A lens opening 21 of substantially rectangular form is provided centrally in the front part 12 with an inverted flange 22 provided along the vertical edges of the lens opening 21. Supporting bracket plates 23 are provided on the inner face of the front part 12 along the edges of the lens opening 21 to receive and support the edges of the lens 19. This may also be clear by referring to Figs. 4 and 5. As will be clear from the drawings, the lens 19 projects through the lens opening 21 and is curved the same from top to bottom as from side to side, as verified by Figs. 4 and 5. The lens opening 21 being located to one side of the front part 12, serves to offset the lens 19 from the front of the lamp and thereby throw the light rays to the side of as well as the front of the machine. This is shown

clearly in Fig. 1, in which view is indicated the result of the specific construction of lamp disclosed in this application.

The lens 19 is provided on its central upper portion with arcuate prisms 24 from the top of the lens 19 to a point slightly below the centre thereof and opposite the centre of the lamp bulb 20 suspended within the lamp structure. The arcuate prisms 24 are curved upwardly toward the upper corner portions of the lens 19 and serve to deflect the light rays and prevent the lamp from sending forth strong central rays known as spotlights, owing to some of the rays of light passing from the lamp bulb 20 directly through the centre of the lens 19. Side prisms 26 are also provided on the outer face of the lens 19 to either side of the central curved or arcuate prisms 24. These side prisms 26 are straight or horizontal and extend from the central curved or arcuate prisms 24 to the sides of the lens 19. It will also be seen from Figs. 2 and 3 that the side prisms 26 are arranged in pairs on the opposite sides of the lens 19 and the lowermost side prisms 26 are slightly above the lowermost central arcuate prism 24. The arcuate prisms 24 and the straight prisms 26 refract and deflect downwardly and sidewise the light rays passing through the lens 19, the side portions of the arcuate prisms 24 producing downward and sidewise deflection while all other portions of prisms 24 and 26 deflect light downwardly only.

The lamp bulb 20 is removably carried on the socket 27 which is preferably suspended on an incline from the upper portion of the front part 12, adjacent its connection with the reflector 10. The current conducting wires 28 connect with the upper end of the socket 27 and then pass through the cushioning ring 18, around the reflector 10 and out of the drum casing 11 by way of the insulating exit ring or eyelet 29 secured in the drum casing 11, preferably at the open side thereof, as shown in Fig. 4. By mounting the socket 27 in the manner stated the lamp bulb 20 is supported at or near the centre of the lamp structure formed by the reflector 10 and the front part 12, thereby placing the lamp bulb 20 concentrically with both of these parts and also concentrically of the lens 19. This will result in the desired reflecting of the rays of light by the reflector 10. As seen in Fig. 1, the position of the lens 19 for the lamps at the opposite sides of the vehicle should be reversed so as to cause spreading of the light to each side of the machine and a crossing of the forwardly directed light rays a short distance in front of the vehicle. This can be accomplished by simply reversing the front part 12 before mounting the lens 19 therein and permitting the reflector 10 for one lamp to be

turned in the reverse direction with respect to the drum casing 11 and then securing the parts of the lamp to one another, as previously stated.

5 The reflector 10 has an eccentric offset portion 30 which is directed rearwardly to accommodate an auxiliary lamp bulb 31 rearwardly of and directly opposite the lamp bulb 20. This auxiliary lamp bulb 31 is 10 suitably secured in the eccentric offset portion 30 of the reflector 10 directly opposite the forward lamp bulb 20. By providing this second or auxiliary lamp bulb 31, however, the strength and volume of light passing through the lens 19 will be considerably increased, owing to the multiplication of light rays thrown to and reflected by the reflector 10. Some of the light rays striking the eccentric offset portion 30 of the reflector 10 will be reflected by this portion of the reflector directly to the lens 19, while other rays of light will first strike this part of the reflector and then be directed to the main part of the reflector 10 before passing through the lens 19. This provides for a thorough diffusing and softening of the light from the lamp. The volume of light directed forwardly will be strong and powerful and will extend as far along the road 20 in front of the machine if not further than the light directed to the side, owing to the placing of the bulbs 20 and 31 in alignment, with one directly back of the other, as shown in the drawings.

35 A modification is disclosed in Fig. 6 which includes the two lamp bulbs 20 and 31, as described and illustrated in the preferred form of the invention. In the form disclosed in Fig. 6, however, the front part 40 12 of the lamp structure has its flange 13' extended around and even with the rear edge thereof. The lens opening 21 in the front part 12 is offset from the centre thereof so as to cause the lens 19 to be positioned 45 to one side of the front part 12 and serve in the same manner as in the other form disclosed. This permits of a placing of the opposed edges of the reflector 10 and the front part 12 even with the forward open 50 side of the drum casing 11. The result in this second form is the same, however, as in the preferred form of the invention and eliminates the necessity of turning the reflector 10 and front part 12 within the 55 drum casing 11. In the last form, the offset portion 30' is practically concentric to the main portion of the reflector 10 so as to position the auxiliary lamp bulb 31 directly opposite and rearwardly of the lamp bulb 20. In the form disclosed in Fig. 6 the lamp bulb 20 is supported slightly inwardly of the forward edge of the reflector 10, while in the preferred form of the invention the lamp bulb 20 is preferably suspended in line 65 with the forward edge of the reflector 10,

as shown clearly in Figs. 4 and 5. Attention is also directed to the fact that the walls of the offset portions 30 and 30' of the reflector 10 in the preferred and modified forms, respectively, are flared and the auxiliary lamp bulbs 31 are located in the rear of such offset portions 30 and 30' and cannot be considered as being located concentrically of said offset portions 30 and 30'. Therefore, many of the rays of light emanating from the auxiliary lamp bulbs 31 will not be thrown back to the same but will be reflected at various angles thereto. This should be clear from reference to Figs. 5 and 6.

The complete construction and operation of the forms of lamp or headlight thus far described should now be apparent to parties familiar with such devices, from the foregoing paragraphs taken in connection with the accompanying drawings, without further detailed description. It may be briefly stated, however, that the parts of the lamp may be readily manufactured at small cost and assembled or taken apart, as desired. When properly positioned and connected, all of the parts will co-operate to throw a soft and diffused light to one side of, as well as forwardly of the lamp and eliminate the spotlight which is objectionable in the conventional forms of headlights now in general use.

In Figs. 7 and 8 a further modification of the invention is disclosed. In this form, the reflector 10' is of semi-spherical shape 100 and is provided with no offset portion of any character. Therefore, the auxiliary lamp bulb employed in the previous forms of the invention is also dispensed with, while the single lamp bulb 20 employed in this new form is suspended concentrically of the reflector 10' and located opposite the edge of the reflector. The lens 19 is supported in the same manner in this form, in the lens opening 21 which is located centrally of the front part 12. This front part 12 and reflector 10' have their edges engaged and are turned at an angle within the cylindrical drum casing 11, as shown more clearly in 110 Fig. 7. The lens 19 is extended concentrically of the lamp bulb 20 and is constructed the same as in the other forms of the lamp and will serve to refract and deflect the light rays and permit spreading of the same forwardly and to one side at practically a right angle to the lamp, the same as in the forms of the invention disclosed in Figs. 1 to 6 inclusive, and clearly indicated in Fig. 1. In fact, the entire structure of this last form is the same as in the other forms with the exceptions noted. All of the parts of the last form, disclosed in Figs. 7 and 8, will function and co-operate 115 in the same manner as the corresponding parts of the other forms. Therefore, the 120 125 130

operation and many advantages of the last form should be clear, without further recital thereof.

When a pair of headlights constructed in accordance with this invention are employed on a vehicle, a substantially even light will be thrown from each headlight in such a manner as to clearly illuminate the surface to either side of the vehicle as well as in front of the same and thereby reduce to the minimum liability of collision with another vehicle on a narrow road or when approaching or turning corners or passing over intersecting roads. It is also evident that the front part 12 of the lamp structure may be readily removed for purposes of repair to the same, for replacing of the lamp bulb 20 or bulbs 20 and 31 or for other purposes and whenever required, the reflector 10 may be removed or replaced, without having to disturb the drum casing 11. Furthermore, the headlights will not have to be turned with the steering gear in order to illuminate the surface to the side of the machine when turning the same, as in the former types of headlights.

While the preferred embodiment of the invention has been disclosed, it is to be understood that minor changes in the details of construction, combination and arrangement of co-operating elements may be resorted to within the scope of what is claimed, without departing from the spirit of the invention.

35. What I claim as new is:

1. A headlight including a curved reflector; a concavo-convex lens opposed to said curved reflector; and light emitting means suspended between said lens and said reflector; said lens being arranged at an angle to the longitudinal center of the headlight and permitting spreading of the light rays forwardly of and to one side of said headlight at an angle of at least ninety degrees; said lens having a transverse, clear lower portion to permit direct rays and also reflected rays of light from the light emitting means to spread over the surface forwardly of and to one side of the headlight; said lens having series of prisms arranged at its upper portion for refracting and deflecting light rays from the light emitting means and from the reflector onto the surface forwardly of and to one side of the headlight and causing a softening of the light rays.

60. 2. A headlight including a curved reflector, a transversely and vertically curved lens connected with said reflector; and light emitting means between said reflector and said lens; said curved lens being provided with a clear curved portion and central and side light refracting and deflecting prisms above and extending to the said clear curved portion from one edge of the lens; said lens

being arranged at an angle to the longitudinal center of the headlight to refract and deflect the light rays from said light emitting means onto the surface forwardly of and to one side of the headlight and also reflected rays of light from said reflector, by means of said prisms.

3. A headlight including a reflector; a bulb within said reflector; and a light refracting and deflecting lens arranged with respect to said reflector and said bulb in such a manner as to refract and deflect the light rays downwardly and sidewise of the lamp as well as in front of the same; said reflector having a rearwardly offset portion; said lens having central curved prisms on its upper portion and straight side prisms on its upper portion; the lowermost curved central prism having its greater portion extending lower than the lowermost straight side prisms; said central and side prisms being located on the outer face of said lens and serving to refract and deflect the light rays passing outwardly through said lens.

4. A headlight including a curved reflector; a lens opposed to said curved reflector; and light emitting means suspended between said lens and said reflector; said lens being constructed and arranged so as to deflect and permit spreading of the light rays forwardly of and to one side of said lamp at an angle of at least ninety degrees; said reflector having a rearwardly offset portion; said lens having central curved prisms on its upper portion and straight side prisms on its upper portion; the lowermost curved central prism having its greater portion extending lower than the lowermost straight side prisms; said central and side prisms being located on the outer face of said lens and serving to refract and deflect downwardly and sidewise the light rays passing outwardly through said lens.

5. A headlight including a reflector; a bulb mounted within said reflector; and a lens opposite said reflector and constructed and arranged to distribute the light rays from the bulb direct and from the reflector to one side of the lamp as well as forwardly thereof; said reflector having a rearwardly offset portion; said lens having central curved prisms on its upper portion and straight side prisms on its upper portion; the lowermost curved central prism having its greater portion extending lower than the lowermost straight side prisms; said central and side prisms being located on the outer face of said lens and serving to refract and deflect downwardly and sidewise the light rays passing outwardly through said lens; said rearwardly offset portion of the reflector being eccentric to the main portion thereof and to the lens.

6. A headlight including a reflector; a bulb within said reflector; a light refracting

- and deflecting lens arranged with respect to said reflector and said bulb in such a manner as to distribute the light rays to one side of the lamp as well as in front of the same; 5 a drum casing for said reflector; a detachable front part for said lamp; said lens being carried in said detachable front part and offset to one side from the open front of the drum casing; the edge of said detachable 10 front part being opposed to the front side of the drum casing and the forward end of the reflector; means for removably securing said front part to said drum casing; means for securing said reflector in set position 15 within said drum casing; and a second auxiliary bulb within said reflector rearwardly of and opposite the first mentioned bulb.
7. A headlight including a reflector; a lens connected with said reflector and corresponding in shape thereto; light emitting means between said reflector and said lens; said lens being constructed and arranged to provide for refracting and deflecting downwardly and sidewise the direct rays of light 20 from said light emitting means and spreading the light rays forwardly of and to one side of the lamp; a drum casing for said reflector; a detachable front part for said lamp; said lens being carried in said detachable front part and offset to one side 25 from the open front of the drum casing; the edge of said detachable front part being opposed to the front side of the drum casing and the forward end of the reflector; means for removably securing said front part to said drum casing; means for securing said reflector in set position within said drum casing; and a second auxiliary light emitting means within said reflector rearwardly 30 of and opposite the first mentioned light emitting means.
8. A headlight including a reflector; a bulb arranged within said reflector; and a lens arranged with respect to said reflector 45 and said bulb to distribute the light rays from said bulb to one side as well as forwardly and downwardly from the lamp; said reflector having a rearwardly offset portion; said lens having central curved 50 prisms on its upper portion and straight
- side prisms on its upper portion; the lowermost curved central prism having its greater portion extending lower than the lowermost straight side prisms; said central and side prisms being located on the outer face of said lens and serving to refract and deflect downwardly and sidewise the light rays passing outwardly through said lens; a drum casing for said reflector; a detachable front part for said lamp; said lens being carried in said 55 detachable front part and offset to one side from the open front of the drum casing; the edge of said detachable front part being opposed to the front side of the drum casing and the forward end of the reflector; means for removably securing said front part to said drum casing; means for securing said reflector in set position within said drum casing; and a second auxiliary bulb within 60 said reflector rearwardly of and opposite the first mentioned bulb; said auxiliary bulb being mounted in said rearwardly offset portion of the reflector.
9. A headlight including a reflector; a bulb within said reflector; and a light refracting and deflecting lens arranged with respect to said reflector and said bulb in such a manner as to distribute the light rays to one side of the lamp as well as in front of the same; said reflector having a rearwardly offset portion; said lens having central curved prisms on its upper portion and straight side prisms on its upper portion; the lowermost curved central prism having its greater portion extending lower than the lowermost straight side prisms; said central and side prisms being located on the outer face of said lens and serving to refract and deflect downwardly and sidewise the light rays passing outwardly through said lens; 70 said reflector and said lens both being arranged concentrically with respect to said bulb; said reflector being of substantially semi-spherical form; said lens being of concavo-convex form and supported practically 75 in the arm partially described by said reflector.
- In testimony whereof, I affix my signature.
- GEORGE E. GLOSSOP.
